UNITED STATES PATENT OFFICE.

HEINRICH BOCKISCH, OF POUGHKEEPSIE, NEW YORK, ASSIGNOR TO M. WELTE & SONS,
OF NEW YORK, N. Y., A CORPORATION OF NEW YORK.

MECHANISM FOR SYNCHRONIZING THE OPERATIONS OF MOVING PARTS.

1,279,640.

Specification of Letters Patent. Patented Sept. 24, 1918.

Application filed April 20, 1916, Serial No. 92,389. Renewed December 20, 1917. Serial No. 208,150.

To all whom it may concern:

Be it known that I, HEINRICH BOCKISCH, a subject of the Emperor of Austria-Hungary, residing at Poughkeepsie, in the county of Dutchess and State of New York, have invented certain new and useful Improvements in Mechanism for Synchronizing the Operations of Moving Parts, of which the following is a specification.

This invention has relation to mechanism for synchronizing the operations of moving parts. As the invention may be very desirably applied to the synchronizing of the operations of a plurality of automatic instruments which respectively reproduce different parts of a musical composition for example, I have selected this particular application of the invention for illustration herein, and particularly have illustrated the preferred embodiment of the invention when it is to be employed as a means for synchronizing the operations of a phonograph—which for the purpose of the present invention is regarded as a species of musical instrument, although its use is not restricted to the reproduction of musical composition—and a pneumatically operable instrument of the style which utilizes a traveling perforated note sheet as the primary selecting element or record, player pianos, automatic organs, and orchestrions, forming well known examples of such pneumatically-operable instruments. In such case, the phonograph may reproduce a solo part of a musical composition and the piano, organ, or orchestrion may reproduce the accompaniment, for example; the mechanism forming the present invention serving so to synchronize the operation of the phonograph and piano, organ, or orchestrion, that the accompaniment notes will be sounded in proper relation to the solo notes. I would have it understood, however, that this particular application of the invention is merely exemplary, as it is not my purpose in any wise to restrict the invention to the synchronizing of phonographs with other musical instruments, however important this particular application may be, because I recognize the fact that the invention may by suitable modification be applied to many different classes of machinery or apparatus, the said modification having reference principally to the substitu-

tion for the herein illustrated "primary controlling elements," which are peculiarly appropriate to a phonograph and self-playing piano, organs or orchestrions, of other primary controlling elements more especially adapted for the particular class or style of machines, apparatuses, or instruments which are to be synchronized.

In the accompanying drawings, wherein like characters of reference denote corresponding parts in the several views:

Figure 1 is a schematic sectional representation of a preferred embodiment of my invention, illustrating, also, certain elements of a phonograph and a self-playing musical instrument to show its preferred application thereto.

Fig. 2 is a wiring diagram of the electrical circuits, showing the positions assumed by the apparatus when speed of the motor is being accelerated, *i. e.*, when contact has been made at A but before the aperture in B is in registration with the special duct.

Fig. 3 is a similar wiring diagram showing the conditions applying after the aperture in B has come into registration with the special duct.

Fig. 4 is a wiring diagram similar to Figs. 2 and 3 but showing the conditions applying when the speed of the wind motor is being decreased, *i. e.*, when the aperture in B is in registration with the special duct before the contact is made at A.

In Figs. 2, 3 and 4 the circuits through which current is flowing are shown in heavy lines.

Fig. 5 is a detail view illustrating one end of a record and tracker board showing special apertures in the record and special duct in the tracker board.

A and B designate two movable or traveling parts whose movements are to be synchronized by the present mechanism. In this particular application of the invention the part A is the table of a phonograph of any approved or suitable kind and the part B is a perforated note sheet such as is commonly employed as the record for playing or controlling the playing of player pianos, piano players, automatic organs, orchestrions and certain other musical instruments. It is well known that in practice the table A is rotated at a regulated speed by a suitable

motor, and hence it is not necessary to illustrate or further refer herein to the mechanism for driving said table. It is also understood that the note sheet or record B is caused in practice to travel at a regulated speed over a tracker board b, and that it is perforated and in its travel over the tracker board opens and closes ducts formed in the latter, these ducts respectively communicating with certain pneumatics of a player action whose nature is such that it controls the operation of the sound-emitting elements of the instrument either by acting directly on appropriate elements of a piano action, as is usual in player pianos, or upon the keys of the piano, as is usual in cabinet piano players, or by opening air passages to reeds or pipes or other sound-emitting elements, as is common in organs or orchestrions, for example. It is apparent that any means of a movable nature which is adapted to open and close the several ducts of the tracker board b, when the latter is employed, in a predetermined succession, may be utilized in lieu of the perforated note sheet B, and hence I would have it understood that the term "record" wherever herein used is intended to comprehend any such device or means. The record B herein shown is wound onto a take-up roll c while playing the instrument and this take-up roll derives motion from a wind motor, illustrated conventionally at C. As it is common in instruments of this class to connect such motors with the take-up roll c for the purpose stated, and as a particular connection of the motor with such roll is in no wise a part of my present invention, I do not consider it essential to describe any particular connection.

Moving with the table A and selector or record B, respectively, are what are herein termed "primary controlling elements," these primary controlling elements controlling the operation of the synchronizing mechanism, which synchronizing mechanism comprises a system of pneumatics and electro-magnets, or the like, so correlated as to produce various effects in the operation of the instrument which effects combine to bring about the correction of the speed of one instrument when it is traveling faster or slower than the other, and to do this so promptly and with such certainty that there is no noticeable lack of synchronization in the operations of the two instruments or machines: it being understood that the record B and the phonograph record—assuming that the instruments to be synchronized are a phonograph and a self-playing piano or the like—or other records which are utilized, have been properly prepared, with reference to each other in the first instance and that the effects which are to be corrected are those due to friction and other conditions which influence the instru-

ments differently and make it advisable to force one instrument to follow every fluctuation in speed of the other.

The present invention aims to secure a practically perfect synchronization of the instruments and further to do this by mechanism of very simple nature, which mechanism includes a system of pneumatically operated valves and means for automatically controlling the same from the primary controlling elements respectively. In this exemplification of the invention, the various valves of the synchronizing mechanism are actuated by or under control of air at atmospheric and less than atmospheric pressures, *i. e.*, air at normal pressure and air at sub-normal pressure. The present day practice in automatic musical instruments being in favor of the utilization of air at sub-normal and normal pressures, rather than normal and above normal pressures, I have illustrated, and prefer, such arrangement herein, without, however, intending to restrict the invention thereto.

The primary controlling element associated with the table A, herein exemplified, is an arcuate metallic strip 10 which is suitably secured to the underside of the table and is insulated therefrom. This strip is arranged to bridge the gap between two yieldable contact elements 11 and 12 during about one-half of each revolution of the table A. The primary controlling element associated with the record B may desirably consist of a series of special apertures 13 formed along an end of said record and arranged intermittently to open a special duct 14 in the tracker board b. This special duct 14 is connected with a chamber 15 which is separated from a suction conduit 16 by a membrane 17. This membrane 17 is connected to a valve 18 which is mounted in a chamber 19 having at one side an atmospheric port 20 and at the other side a port 21 which opens into the conduit 16. The chamber 19 also has a duct 22 which extends to a pneumatic 23 provided with a projection 24. The ports 20 and 21 are so arranged with relation to the valve that the latter in one position closes the port 21 and opens the port 20 and in the other position closes the port 20 and opens the port 21. The closing of the port 20 and opening of the port 21 occurs each time a synchronizing aperture 13 comes into registration with the special duct 14, and at this time the pneumatic 23 is under suction from the conduit 16 and is collapsed. The opening of the port 20 and the closing of the port 21 occurs each time the duct 14 is closed, and at this time air at atmospheric pressure is admitted to the pneumatic 23 and the latter is expanded. The collapsing of the pneumatic 23 closes an electrical conduit as hereinafter set forth.

The wind motor C derives motion from a

conduit 25 with which it is suitably connected. This conduit contains air at sub-normal or suctional pressure, and the pressure of this air is regulated automatically by the synchronizing mechanism under control of the primary controlling elements hereinbefore referred to. It may here be stated that the conduit 16 is supplied with strong unregulated suction while the suction in conduit 25 is a relatively weak regulated suction.

When the motor is traveling too slowly the conduit 25 is placed under greater suction through a duct 26 which extends to a chamber 27 having a port 28 leading to a suction conduit, the suction conduit in this exemplification being the conduit 16 hereinbefore referred to. The chamber 27 contains a valve 29 whose stem 29^a is connected to a membrane 30 which separates the conduit 16 from a chamber 31 having a duct 32 through which it may be opened to the atmosphere. Obviously the opening of the chamber 31 to the atmosphere will cause the valve 29 to move and place the duct 26 in communication with the conduit 16, which will effect a further attenuation of the air in the conduit 25. The duct 26 may be provided with means for regulating the opening therethrough. This means may desirably comprise an adjustable threaded member 33 extending through a block 34 into the duct 26 and adjustable to restrict the aperture through the latter. The chamber 27 should be permanently closed against the atmosphere and for this reason, and at the same time to provide proper guidance for the valve stem, 29^a, I prefer to extend said stem through a guiding member 35, the opening through which is covered by a flexible air-tight apron 35^a of approximately inverted cup shape, whose edge is secured in an air-tight manner to said member, the apron being also connected, at its center in an air-tight manner to a nut 29^c which moves with the stem 29^a and being adapted to move with the stem without discharging its function of preventing leakage around the stem. A spring 36 may be provided to assure the quick return of the valve 29 to its seat over the port 28 when the duct 32 has been closed.

When the wind motor is traveling too fast it is slowed down by reducing the suctional force in the conduit 25. This is accomplished, in the herein exemplified form of the invention, by opening the conduit 25 to the atmosphere through a port 37, chamber 38 and port 39. This port is provided with an adjustable threaded member 33^a to restrict the opening through said port. It will be seen that the provision of the members 33 and 33^a renders it unnecessary to accurately adjust the throw of the valves 29 and 40 because the forces effective when said valves are actuated may be efficiently regu-

lated by said members 33 and 33^a. The port 37 is closed by a valve 40 which is carried by a membrane 41. This membrane 41 divides the chamber 38 from a second chamber 42, and a spring 43 in the second chamber is arranged to hold the valve 40 normally over the port. The second chamber 42, has a duct 44 extending thereto from a chamber 45. This chamber 45 is provided with an atmospheric port 46 and a suction port 47 and in it is mounted a valve 48 which opens these ports alternately. When the atmospheric port 46 is open, air at atmospheric pressure is admitted to the chamber 42 through the chamber 45 and duct 44, and this, together with the spring 43, holds the valve 40 tightly to its seat over the port 37. When the port 47 is open, air at sub-normal pressure is admitted to the chamber 45 and thence to the chamber 42, whereupon the membrane 41 will be moved to carry the valve 40 away from the port 37, thus opening the conduit 25 to the atmosphere through the port 37, chamber 38 and port 39.

In this exemplification of the invention valve 48 has its stem 48^a connected to a membrane 49 which separates the suction conduit 16, hereinbefore referred to, from a chamber 50 having an atmospheric duct 51. Thus the valve 18 which controls the collapse and expansion of the pneumatic 23, the valve 29 which controls the further attenuation of the air in the regulated-wind conduit 25 and the valve 48 which controls the reduction of the suctional force of the air in said conduit 25, together with their operating membranes are all mounted in a single chest having a suctional conduit (16) common to all the valve chambers. This is desirable but not essential to the invention. The several chambers 15, 50 and 31 in the herein exemplified form of the mechanism are connected with the suction conduit 16 by bleed holes marked 15^a, 50^a and 31^a, respectively.

D, E, F, G, H, and I designate suitable electric motors by which the opening and closing of certain ducts are controlled from the primary controlling elements. In this exemplification of the invention these motors are electro-magnets whose armatures are marked *d*, *e*, *f*, *g*, *h*, and *i*, respectively, said armatures serving as valves for the ducts hereinafter particularly referred to.

The armatures *h* and *i* are arranged in operative relation with the ducts 32 and 51, respectively. Hence when the magnet *H* is energized, the duct 32 will be opened admitting air to the chamber 31, whereupon the valve 29 will be moved from the position shown in Fig. 1 and the suction conduit 25 will be opened to the suction conduit 16 and a further attenuation of the air in the conduit 25 will be brought about. Similarly, when the magnet *I* is energized the armature *i* will be attracted and the chamber 50 will

be opened to the atmosphere, whereupon the valve 40 will be moved from the position shown in Fig. 1, resulting in the opening of the port 37 and the lessening of the suctional force within the conduit 25.

The magnets F and G have their armatures *f* and *g* respectively arranged in operative relation with branch ducts 52 and 53, both of which are connected to a chamber 54 in a valve box J. In this particular exemplification of the invention the connection of the branch ducts 52 and 53 with said chamber 54 includes ducts 55 and 56. The magnets D and E have their armatures *d* and *e* respectively arranged in operative relation with branch ducts 57 and 58, both of which are connected with a chamber 59 in a valve box K, the connection in this exemplification of the invention comprising the duct 60.

The valve box J has a suction conduit 61 which is separated from the chamber 54 by a membrane 62 and is connected with said chamber by a bleed hole 61^a. Said valve box also has a chamber 63 having a port 64 through which it has communication with the conduit 61 and a port 65 through which it has communication with the atmosphere. In the chamber 63 there is mounted a valve 66 whose stem 66^a is connected to the membrane 62. The valve box K is similarly constructed: 67 designating a suction conduit: 67^a the bleed hole to the chamber 59: 68 the membrane separating the chamber 59 from the conduit 67: 69 the valve chamber: 70 the suction port to said chamber: 71 the atmospheric port to said chamber: 72 the valve in said chamber: and 72^a the valve stem.

L and M designate other boxes respectively. The valve box L is provided with a chamber 73, a port 74, a chamber 75, a membrane 76 and a chamber 77. The port 74 opens at one end into the chamber 73 and at its other end into the chamber 75 and the membrane 76 separates the chamber 75 from the chamber 77. The port hence may be thrown into communication with chamber 73 or chamber 75 and this communication is controllable, preferably, by valves 78 and 79 arranged on a stem 80 which is connected to the membrane 76 and is also preferably connected with a spring 81 whose tendency is such as to hold the valve 79 normally closed and the valve 78 normally open. The valve box M is of similar construction: 82 designating the chamber corresponding to chamber 73: 83 designating the port: 84 designating the chamber corresponding to chamber 75: 85 designating the membrane: 86 designating the chamber corresponding to chamber 77: 87 and 88 designating the valves: 89 the stem upon which these valves are mounted and 90 the spring.

The chamber 73 of box L and the chamber 86 of box M are connected with each other

through a duct 91, which also has communication with the chamber 63 of the box J through a branch 91^a. The chamber 77 of box L and chamber 82 of box M are connected with each other through a duct 92 which also has communication with the chamber 69 of box K through a duct 92^a. Hence it will be noted that the membrane chamber 86 of box M and chamber 73 of box L will be under suction whenever chamber 63 is under suction and will contain air at atmospheric pressure whenever said chamber 63 is open to the atmosphere, and similarly that the membrane chamber 77 of box L and chamber 82 of box M will be under suction whenever chamber 69 of box K is under suction and will contain air at atmospheric pressure whenever said chamber 69 is open to the atmosphere. It may also be mentioned that chambers 75 and 84 of boxes L and M respectively are always open to the atmosphere and hence when chamber 77 of box L is placed under suction the valves 78 and 79 will be moved to cut off communication of port 74 with chamber 73 and open communication of said port with chamber 75, and similarly whenever chamber 86 of box M is under suction the valves 87 and 88 will be moved to cut off communication of the port 83 with the chamber 82 and open communication of said port with the chamber 84. Said port 74 of box L is connected with a bellows 93 by a duct 94, and said port 83 of box M is connected with a bellows 95 by a duct 96.

It will now be seen that when the magnet D is energized, valve 72 in box K will be raised and chamber 82 in box M will be in communication with suction conduit 67 through port 70, chamber 69, branch duct 92^a and the portion of duct 92 leading from the branch duct 92^a to the chamber 82, and as the way through the port 83 and duct 96 to the bellows 95 is now opened, said bellows will be subjected to suctional force and hence collapsed. At the same time, the chamber 77 of box L will be under suction from said conduit 67, communicated thereto through the port 70, chamber 69, branch duct 92^a and the part of the duct 92 leading from the branch duct 92^a to the chamber 77: thus closing the port 74 of box L against communication with chamber 73 and opening it to communication with the atmosphere, through chamber 75, instead of through chamber 73, the portion of duct 91 between branch duct 91^a and chamber 73, said branch duct 91^a, chamber 63 and atmospheric port 65, as formerly. Hence bellows 93 remains expanded whereas bellows 95 has been collapsed. When magnet E is energized before magnet D is deenergized, it finds the bellows 95 collapsed and the bellows 93 expanded and as its armature *e* controls a branch (58) leading from the same duct (60) which has another branch (57) controlled by the arma-

ture of magnet D, and through the opening of which duct 60 the foregoing operations were effected, it follows that the energizing of the magnet E does not change the condition, but said magnet is able to continue said conditions until it is deenergized, or in other words, after the magnet D has been deenergized.

It will further be seen that when the magnet G is energized at a time when the other magnets are all deenergized, chamber 54 is opened to the atmosphere through branch duct 53, duct 56 and duct 55, and that the opening of this chamber to the atmosphere causes the valve 66 of box J to move and open chamber 63 to the suction conduit 61. This places chamber 73 of box L under suction and as bellows 93 is at this time in communication with said chamber 73 the bellows will be collapsed. Chamber 86 of box M being also in communication with chamber 63 of box J will be placed under suction and this will act to move the valves 87 and 88 and cut off communication of port 83 with chamber 82 and open communication of said port with chamber 84. Bellows 95 is now in communication with the atmosphere through chamber 84, port 83 and duct 96 and hence remains expanded. If now, while the magnet G is still energized, the magnet F becomes energized it will find the bellows 93 collapsed and the bellows 95 expanded and will not change this condition, because its branch duct 52 has communication with the chamber 54 through duct 55 and this duct 55 forms a part of the communication between duct 53 and chamber 54. The duct 52, however, being connected to the chamber 54 will result in the chamber 54 remaining open to the atmosphere after duct 56 and branch duct 53 have been closed, that is to say, after magnet E has become deenergized and until said magnet F is deenergized.

It may be here mentioned that when the several valves are in the positions shown in Fig. 1 both bellows are expanded, the bellows 93 being in communication with the atmosphere through duct 94, port 74, chamber 73, branch duct 91^a, that part of duct 91 which is between the branch duct 91^a and the chamber 73, chamber 63 and the port 65: while the bellows 95 is in communication with the atmosphere through duct 96, port 83, chamber 82, that part of duct 92 which is between chamber 82 and branch duct 92^a, said branch duct 92^a, chamber 69 and port 71.

The movable board of the bellows 93 carries a contact bridging element 97 and the movable board of the bellows 95 carries a contact bridging element 98, these elements being of such nature that they may form parts of electrical circuits preferably formed by the connection now to be explained.

N designates a suitable source of electrical energy of low voltage. From the positive

terminal of this source a wire 100 extends and terminates in the contact 11. From the complementary contact 12 a wire 101 extends to a terminal 102 common to the magnets D and F. From the other terminal 103 of the magnet D a wire 104 extends to a contact 105. This contact 105 is separated from a second contact 106, and these two contacts are adapted to be bridged by the bridging element 97 of the bellows 93 when the bellows is expanded. From the contact 106 a wire 107 extends to a terminal 108 carried by a bus bar 109 having another terminal 110. From the terminal 110 a wire 111 extends back to the negative terminal of the source N. From the positive terminal of the source N a wire 112 extends to a terminal 113 on a bus bar 114, said bus bar having a second terminal 115, from which a wire 116 extends to a contact element 117, which is adjacent to a second contact element 118, from which a wire 119 extends to a terminal 120, common to the magnets E and G.

From the other terminal 121 of the magnet E a wire 122 extends to a terminal 123 having a contact element 124 which is separated from complementary contact elements 125, 124^a and by spaces adapted to be bridged by the contact bridging element 98 on the movable board of the bellows 95 when the said bellows is collapsed. The terminal 126 of the contact element 125 is connected by a wire 127 to a terminal 128 on the bus bar 109.

Associated with the bellows 93 are three similar spaced contacts 129, 129^a and 130 which are bridged by the contact bridging element 97 when the bellows is collapsed. The contact 129 extends from a terminal 131 which is connected by a wire 132 with a terminal 133 of the magnet F, the contact 129^a is carried by a terminal 131^a, said terminal being connected by a wire 134 with a terminal 135 of the magnet I. A bus bar 136 has a terminal 137 to which the other side of the magnet I is connected, the bus bar also having a terminal 138 to which one side of the magnet H is connected. The bus bar 136 is also connected to the bus bar 114 by a wire 139 which extends from a terminal 140 on the bar 114 to a terminal 141 on the bar 136. The contact 130 of the bellows 93 extends from a terminal 142 which is connected by a wire 143 with the terminal 108 of the bus bar 109.

Associated with the bellows 95 are two other contacts 144 and 145, which are bridged by the contact bridging element 98 when the bellows 95 is expanded. The terminals of these contacts are connected by the wires 146 and 147 with the terminal 148 of the magnet G and the terminal 128 on the bus bar 109, respectively. From a terminal 149 of the magnet H a wire 150 extends to a terminal 123^a having the contact 124^a, hereinbefore mentioned, associated with the bellows 95.

From the foregoing the operation will be readily understood to be as follows:

Three possibilities in the relative movements of the table A and record B are apparent, to wit: first, the speed of the table may be such that its contact bridging element 10 is in engagement with the contacts 11 and 12 before a synchronizing aperture 13 of the record B is in registration with the duct 14, in which event the wind motor C must be speeded up: second, said contact bridging element 10 may come into engagement with the contacts 11 and 12 after a synchronizing aperture 13 of the record has come into engagement with the duct 14, in which case the wind motor C must be slowed down; third, the contact bridging element 10 may come into engagement with the contacts 11 and 12 at the same moment that a synchronizing aperture 13 comes into registration with the duct 14, in which case the table A and record B are traveling in synchronism and the synchronizing mechanism should not operate to either bring about an increase or a reduction in the speed of the wind motor.

Assuming now that the contact bridging element 10 is in engagement with the contacts 11 and 12 before a synchronizing aperture 13 comes into registration with the duct 14, the circuit will be closed through the magnet D, said circuit traversing the following course: (see Fig. 2): wire 100, contact 11, bridging element 10, contact 12, wire 101, magnet D, wire 104, contact 105, contact bridging element 97, contact 106, wire 107, terminal 108, bus bar 109, terminal 110 and wire 111. The magnet D being now energized, its armature *d* is attracted and the branch duct 57 and duct 60 leading to chamber 59 are opened to the atmosphere. Chamber 59 being now in communication with the atmosphere the valve 72 is moved to open communication of chamber 69 with the suction conduit 67 and close communication of said chamber 69 with the atmosphere. Two results follow, to wit:

(a) The chamber 77 of valve box L is placed under suction, whereupon the valves 78 and 79 are moved to cut off communication of port 74 with the chamber 73 and open communication of said port with the atmosphere through chamber 75, and hence the bellows 93 will now be in communication with the atmosphere through duct 94, port 74 and chamber 75, thereby assuring the maintenance of said bellows in its expanded condition, it being understood that when the chamber 77 is not under suction the valves 78 and 79 will be held in the position shown in Fig. 1 by the spring 81.

(b) The valves 87 and 88 of valve box M being in the position shown in Fig. 1, bellows 95 will be collapsed by reason of its communication with the suction conduit 67 af-

firmed through duct 96, port 83, chamber 82, 65 that portion of the duct 92 between said chamber 82 and the branch 92^a, branch duct 92^a, chamber 69 and port 70; thereby causing the contact bridging element 98 to bridge the space between the contacts 124, 124^a and 125. The circuit through magnet H will be closed, this circuit taking the following course: from the positive terminal of the source N to terminal 113 of bus bar 114, by way of the wire 112, thence to terminal 140, 70 thence by wire 139 to the terminal 141 on the bus bar 136, thence from terminal 138 on said bar, through the magnet H, and by wire 150 to terminal 123^a and contact 124^a, thence through bridging element 98 to contact 125, 75 terminal 126, wire 127 to terminal 128 on bus bar 109, thence to terminal 110 and thence by wire 111 to the negative terminal of the source N.

The energizing of the magnet H opens the 85 duct 32 to the atmosphere and this causes the valve 29 to move and open the chamber 27 to the suction conduit 16, and as the chamber 27 is in communication with the suction conduit 25 it will follow that additional 90 suctional force will be introduced into said suction conduit 25 and the air therein further attenuated so that the motor C will receive a suctional impulse of added 95 strength.

This is the condition of the parts when the synchronizing aperture 13 comes into registration with the duct 14, whereupon atmospheric air will be admitted to chamber 15 and this will cause the valve 18 to move 100 and close chamber 19 against the atmosphere and open it to the suction conduit 16, thus collapsing the bellows 23 and closing the following circuit through magnet E, to wit: 105 (see Fig. 3).

From positive terminal of source N, by wire 112 to the terminal 113 on bus bar 114, thence to terminal 115 on said bar, thence by wire 116 to contact 117, contact 118 and by wire 119 to terminal 120, thence through 110 magnet E, terminal 121, wire 122 to terminal 123, to contact 124, through bridging element 98, contact 125, wire 127, terminal 128, bus bar 109, terminal 110 and wire 111 back to the negative terminal of the source. 115

The energizing of the magnet E causes its armature *e* to be attracted and hence opens the branch duct 58 to the atmosphere. This duct 58 is connected to the duct 60 which, as we have already seen, was opened to the atmosphere when the armature *d* of the magnet D was attracted. The result is that no change in the condition of the parts takes place and in fact the magnet H will not be deenergized until the magnet E has been deenergized: in other words magnet D will be deenergized before magnet E because it was energized first, but magnet H remains 120 125

energized and the additional suction is introduced into conduit 25 until both magnets D and E have been deenergized, the deenergizing of magnet D alone, which takes place when the bridging element 10 has passed out of engagement with the contacts 11 and 12, merely serving to close the branch duct 57, the duct 60 still remaining in communication with the atmosphere through the duct 58, until magnet E has been deenergized.

Both magnets having been deenergized and duct 60 having been closed, valve 72 will be moved to cut off communication of chamber 69 with the suction conduit 67 and open communication of said chamber with the atmosphere, whereupon air at atmospheric pressure will be admitted to bellows 95 and the latter expanded to break the circuit to magnet H and to bridge the gap between the contacts 144 and 145. At the same time air at atmospheric pressure from the chamber 69 will be conducted by the duct 92 to chamber 77 of valve box L thereby permitting spring 81 to act to adjust the valves 78 and 79 to the positions in which they close the port 74 against the atmospheric chamber 75 and open it to the chamber 73. It will be noted that this chamber 73 is now in communication with the atmosphere through the port 65, chamber 63 and branch duct 91^a of the valve box J leading to the duct 91 so that the bellows 93 will remain expanded. The parts are now in their original position ready for a new operation. If the synchronizing hole 13 still comes into registration with its duct 14 after the circuit through magnet D has been closed, the foregoing operation will be repeated.

If, on the other hand, the synchronizing aperture 13 comes into registration with its duct 14 before the circuit through the magnet D has been closed, that is, before the contacts 11 and 12 are bridged by the bridging element 10, the operation will be as follows:—The collapsing of the bellows 23 will close the circuit through magnet G, this circuit being as follows:—(see Fig. 4) from positive terminal of the source N by the wire 112 to terminal 113, thence over the bus bar 114 to terminal 115, thence by wire 116 to contact 117, thence by contact 118 and wire 119 to terminal 120, thence through the magnet G, thence by wire 146 to contact 144, thence by bridging element 98 and contact 145 and wire 147 to terminal 128, thence over bus bar 109 to terminal 110, thence by wire 111 to the negative terminal of the source N.

The energizing of this magnet G attracts its armature 9 and opens the branch duct 53 and ducts 55 and 56 to the atmosphere, thus placing chamber 54 of valve box J in communication with the atmosphere. This

causes the valve 66 in said box to move and open the chamber 63 to the suction conduit 61 and close it against the atmosphere. Its chamber 63 is in communication with the chamber 73 of valve box L and also with the chamber 86 of valve box M. Hence valves 87 and 88 of valve box M will be moved to close port 83 against chamber 82 and to open said port to the atmospheric chamber 84: air at atmospheric pressure is now conducted by duct 96 to the bellows 95 and keep the latter in its expanded condition. At the same time, the bellows 93 being in communication with the chamber 73, which is under suction, said bellows 93 will be collapsed thus moving contact bridging element 97 out of engagement with contacts 105 and 106 and causing it to bridge the contacts 129 and 129^a and 130, whereupon the circuit through the magnet I will be closed, this circuit traversing the following course:—

From positive terminal of source N by wire 112 to terminal 113, bus bar 114 to terminal 140, thence by wire 139 to terminal 141 on bus bar 136, thence to terminal 137 through magnet I to terminal 135, thence by wire 134 to terminal 131^a and contact 129^a, thence through bridging element 97 to contact 130 and terminal 142 and by wire 143 to terminal 108 on bus bar 109 and to terminal 110 on said bar and by wire 111 to the negative terminal of the source. When the contact bridging element 10 on the table A is brought into engagement with the contacts 11 and 12 the circuit is closed through magnet F, this circuit traversing wire 100, contact 11, bridging element 10, contact 12, wire 101 to terminal 102, thence through magnet F and by way of wire 132 to the terminal 131 and contact 129, bridging element 97, contact 130, terminal 142, wire 148, terminal 108, bus bar 109, terminal 110 and wire 111 to the negative terminal of the source.

The energizing of this magnet F opens the branch duct 52 to the duct 56 and is without effect until the branch duct 53 has been closed whereupon it becomes effective to keep the chamber 54 open to the atmosphere and thus maintain the parts in their former positions until it, namely the magnet F, has been deenergized, or in other words until both the synchronizing aperture 13 and the contact bridging element 10 have passed out of operative relation with the duct 14 and contacts 11 and 12, respectively.

When the synchronizing aperture 13 comes into registration with the duct 14 at the same moment that the contact bridging element 10 comes into engagement with the contacts 11 and 12, magnets D and G will, as is apparent, be energized at the same time. This will result in the simultaneous move-

ment of the valve 72 in the box K and the valve 66 in the box J, whereby chamber 85 will be placed under suction through duct 91, branch duct 91^a, chamber 66 and port 64

full speed. For the latter purpose it may be given an additional starting impulse by hand or by mechanism, which ever is preferred.

Having now described the invention and set forth in detail the preferred embodiment and application thereof, what I believe to be new and desire to secure by Letters Patent is:—

- 5 from chamber 61 and chamber 77 will be placed under suction through duct 92, branch duct 92^a, chamber 69 and port 70, from chamber 67. This will result in lifting the valves 78, 79 and 87, 88 simultaneously to thereby close the outlet from chambers 73 and 82 through ports 74 and 83, respectively and prevent suction from passing to either bellows 93 or 95. In other words if the parts A and B complete their 15 respective circuits exactly together, the synchronizing function of either of said parts is neutralized by the other and no change in the speed of the wind motor results.
- 20 It has been stated in substance that when valve 72 is opened first by the energizing of the motor D first, it is maintained in such open position as long as motor E is energized or, in other words, it is maintained in 25 such open position until the contact bridging element 10 passes out of engagement with contacts 11 and 12 and the synchronizing aperture 13 has passed out of registration with the duct 14: and, similarly that
- 30 when valve 66 has been opened by the energizing of motor G it will continue open until motor F has been deenergized. This explanation is founded upon the supposition that the motor which has been energized 35 first will be deenergized first. This, however, may not always be true, as it is possible, in the operation of the apparatus, that the motor which has been energized first will be deenergized at the same time as or 40 later than the motor which has been energized second. If it is deenergized ahead of the companion motor which was energized after it was energized, then the valve 66 or 72, associated with said motor, obviously will be maintained in its open position until the motor which operated to open it has been deenergized. In other words, the parts are so coördinated that either valve will remain in open position as long 50 as either motor associated therewith is energized.

It of course will be understood that the records are prepared with reference to each other and when one of the records is a phonograph record it should have means of some appropriate nature for indicating or determining the position in which it is laid upon the phonograph table. Again it will be understood that both instruments should be 55 started at the same time and at the same speed. When one of the instruments to be synchronized is a phonograph it will be desirable, though not essential, to provide means whereby the table will be started at 60 the full speed or will quickly attain such

1. Mechanism for synchronizing the operations of moving parts comprising, in combination, a motor for one of the parts and periodically operative connections controlled in accord with the moving parts, respectively, and respectively effecting an increase 75 and decrease of the speed of the motor, said connections including means for causing that moving part which is traveling in advance of the other to first affect the motor to increase or decrease its speed and the 80 other of said moving parts to continue said effect upon the motor throughout the period of operation of the latter moving part if the first-named moving part ceases to exert its effect.

2. Mechanism for synchronizing the operations of moving parts comprising, in combination, a motor for one of the parts, valves, means whereby movement of the valves effects an increase or decrease of the 85 speed of the motor respectively, motors for said valves, respectively, and periodically operative connections between the valve motors and the parts to be synchronized, said connections including means operating in 90 accord with the moving parts for causing that part which is traveling in advance of the other to first set in operation its related valve motor and the other of the moving parts to act to continue the operation of said 95 valve motor if the first named part ceases to exert its effect.

3. Mechanism for synchronizing the operations of moving parts comprising, in combination, a motor for one of the parts, pneumatically operable valves, means whereby movement of the valves effects an increase or decrease of the speed of the motor, respectively, electric motors for controlling the pneumatically operable valves periodically operative connections between the said 100 electric motors and the parts to be synchronized, said connections including means operating in accord with the moving parts respectively, for causing that moving part which is traveling in advance of the other to first set in operation its related electric motor and the other of the moving parts to act to continue the operation of the said 105 electric motor if the first named part ceases to 110 exert its effect thereon.

4. Mechanism for synchronizing the operations of moving parts comprising, in combination, a motor for one of the parts, pneumatically operable valves, means whereby 115

movement of the valves effects an increase or decrease of the speed of the motor, respectively, electric motors for controlling said valves, electric circuits between the electric motors and the parts to be synchronized, means for periodically completing said circuits under the action of the said parts respectively, and means in said circuits for causing that moving part which is traveling in advance of the other to complete one of said circuits to set one of the electric motors in operation and the other of the moving parts to then complete a circuit to continue the operation of said motor, if the circuit made by the first named moving part is broken.

5. Mechanism for synchronizing the operations of moving parts comprising, in combination, a motor for one of the parts, valves, means whereby movement of the valves effects an increase or decrease of the speed of the motor, respectively, electric motors for controlling said valves, a circuit for each of said motors, a circuit making and breaking element in each of said circuits, and periodically operative connections for operating the circuit making and breaking elements under control of the parts to be synchronized, respectively, said connections including means whereby during the time that one of the said making and breaking elements is actuated to close the circuit to one of the electric motors the other of said circuit making and breaking elements is caused to break the circuit to the other of said motors, said connections also including means whereby that moving part which is traveling in advance of the other will first act to complete the circuit to one of the motors and the other of the moving parts will act to maintain the completion of said circuit if the first named part ceases to exert an effect thereon.

6. Mechanism for synchronizing the operations of moving parts comprising, in combination, a motor for one of the parts, valves, means whereby movement of the valves effects an increase or decrease of the speed of the motor respectively, motors for said valves, respectively, and periodically operative connections between the valve motors and the parts to be synchronized, said connections including means whereby that moving part which is traveling in advance of the other will first set in operation its related valve motor and the other of the moving parts will act to continue the operation of said valve motor after the first named part ceases to exert its effect upon said valve motor, said connections further including means whereby when one of the valve motors is set in operation the connections are rendered inoperative with respect to the other of the valve motors.

7. Mechanism for synchronizing the operations of moving parts comprising, in combination, a motor for one of the parts, valves, means whereby movement of the valves effects an increase or decrease of the speed of the motor respectively, means for actuating the valves, electric motors for controlling said actuating means, a circuit for each of

said motors, a circuit making and breaking element in each of said circuits and periodically, operative connections for operating the circuit making and breaking elements under control of the parts to be synchronized respectively, said connections including means whereby during the time that one of the said making and breaking elements is actuated to close the circuit to one of the electric motors the other of said circuit making and breaking elements is caused to break the circuit to the other of said motors, said connections also including means whereby that moving part which is traveling in advance of the other will first act to complete the circuit to one of the motors and the other of the moving parts will act to maintain the completion of said circuit if the first named part ceases to exert an effect thereon.

8. Mechanism for synchronizing the operations of moving parts comprising, in combination, a driving motor for one of the parts, a plurality of electric motors, means between the electric motors and the driving motor whereby the energizing of the electric motors effects an increase or decrease of the speed of the driving motor, respectively, and means for energizing said motors, comprising an electric circuit for each motor, a circuit making and breaking element for each of said circuits, electric circuits periodically closed by the aforesaid moving parts respectively, and connections between the last named circuits and the circuit making and breaking element, respectively, said connections including a series of motors arranged in pairs, one motor of each pair being in one circuit and the other motor of each pair being in the other circuit, whereby one motor of either pair when energized will effect the operation of its associated circuit making and breaking element and the other motor of the same pair may continue such effect after the first-named motor has been deenergized.

9. Mechanism for synchronizing the operations of moving parts comprising, in combination, a driving motor for one of the parts, a plurality of electric motors, means between the electric motors and the driving motor whereby the energizing of the electric motors effects an increase or decrease of the speed of the driving motor, respectively, and means for energizing said motors, comprising an electric circuit for each motor, a pneumatically operable circuit making and breaking element for each of said circuits, electric circuits periodically closed by the aforesaid moving parts respectively, valvular means for operating the circuit making and breaking elements respectively, and means for controlling the operation of the valvular means under control of the last-named circuits, the controlling means including a series of electric motors, arranged in

pairs, one motor of each pair being in one circuit and the other motor of each pair being in the other circuit, and connections between said pairs of motors and the valvular means respectively.

10. Mechanism for synchronizing the operations of moving parts, comprising in combination, a motor for one of said parts and means for effecting an increase or decrease of the effective strength of the forces exerted upon the motor, said means including pneumatically operable circuit making and breaking devices, valves for controlling the pneumatic forces by which said devices are actuated, ducts, the opening of which causes the actuation of said valves, a plurality of controlling devices for each of the ducts and means for operating said controlling devices successively under control of the moving parts respectively.

11. Mechanism for synchronizing the operations of moving parts, comprising, in combination, a motor for one of said parts and means for effecting an increase or decrease of the effective strength of the forces exerted upon the motor, said means including pneumatically operable circuit making and breaking devices, valves for controlling the pneumatic forces by which said devices are actuated, ducts, the opening of which causes the actuation of said valves, a plurality of branches for each duct, an electrical controlling device for each of the ducts and means for operating said controlling devices successively under control of the moving parts respectively.

12. Mechanism for synchronizing the operations of moving parts, comprising in combination, a motor for one of said parts and means for effecting an increase or decrease of the effective strength of the forces exerted upon the motor, said means including pneumatically operable circuit making and breaking devices and connections between said devices and the motor, primary valves controlling the pneumatic forces by which said devices are actuated, additional valves which when in one position permit the passage of pneumatic forces of one strength to the said devices and when in the other position permit the passage of pneumatic forces of another strength to the said devices, actuating means for each of the additional valves, ducts controlled respectively by the said additional valves and communicating respectively with the actuating means of the other of said additional valves, chambers in which the primary valves are located, and connections between said chambers and the ducts respectively.

13. Mechanism for synchronizing the operations of moving parts, comprising in combination, a motor for one of said parts and means for effecting an increase or decrease of the effective strength of the forces

exerted upon the motor, said means including pneumatically operable circuit making and breaking devices and connections between said devices and the motor, primary valves for controlling the pneumatic forces by which said devices are actuated, additional valves which when in one position permit the passage of pneumatic forces of one strength to the said devices and when in the other position permit the passage of pneumatic forces of another strength to the said devices, actuating means for each of the additional valves, ducts controlled respectively by the said additional valves and communicating respectively with the actuating means of the other of said additional valves, chambers in which the primary valves are located, connections between said chambers and the ducts, respectively, and a plurality of controlling means for each of the primary valves, said latter means being operable successively under control of the moving parts respectively.

14. Mechanism for synchronizing the operations of moving parts, comprising in combination, a pneumatically controlled motor for one of said parts, valves controlling the pneumatic forces to increase or decrease the speed of the motor respectively, electric members respectively controlling said valves, an electric circuit for each of said members, a pneumatically operable circuit making and breaking device included in each of the circuits, valves and connections between said valves and the pneumatically operable circuit making and breaking devices whereby said devices are controlled respectively by said valves, a plurality of electric motors controlling the movement of each of said valves, circuit closing means operable periodically under control of the moving parts, respectively, and a plurality of electric circuits in which the circuit closing means, the electric motors and the circuit making and breaking devices are included, the electrical connections being so arranged, that when one of the circuit closing means is actuated in advance of the other, a circuit is completed through one of the electric motors with which it is associated to move the valve that is controlled thereby and also closes the circuits in which the other electrical motor is included whereby when the other circuit closing means is moved, said electric motor is energized to continue the actuation of said valve and to thereby continue the pneumatic operation of said circuit making and breaking devices.

15. Mechanism for synchronizing the operations of moving parts, comprising, in combination, a driving motor for one of the parts, a plurality of electric motors, means between the electric motors and the driving motors whereby the energizing of the electric motors effects an increase or decrease of

- the speed of the driving motor, respectively, and means for energizing said motors, comprising an electric circuit for each motor, a circuit making and breaking element for 5 each of said circuits, connections through which the movements of the circuit making and breaking devices are respectively effected, valves in said connections, a plurality of controlling motors arranged in pairs, each 10 pair controlling one of said valves, a pair of primary electric circuits and circuit closing means therein, said circuit closing means being actuated under control of the moving parts respectively, one of the motors of each 15 pair being included in the respective primary circuits and circuits controlled by the circuit making and breaking elements and in which circuits said motors are included, the connections for said circuits being so arranged 20 that when one of the primary circuits is closed in advance of the other one of the controlling motors of a pair will be energized to cause the actuation of its associated valve and when the other primary 25 circuit is later closed the other controlling motor of that pair will act to continue such actuation of the valve.
16. Mechanism for synchronizing the operations of moving parts, comprising, in 30 combination, a motor for one of said parts, and means for effecting an increase or decrease of the effective strength of the forces exerted upon the motor, said means including pneumatically operable circuit making 35 and breaking devices, valves, and connections between said valves and the pneumatically operable circuit making and breaking device, said valves controlling the pneumatic forces by which said devices are actuated, a 40 plurality of electric motors for controlling the movement of each of said valves, means for energizing said motor successively under control of the moving parts, respectively, and connections between the valves whereby 45 when said valves are simultaneously opened they each act to cut off communication between the other and the pneumatic circuit making and breaking device controlled by the latter.
- 50 17. Mechanism for synchronizing the operations of moving parts, comprising, in combination, a motor for one of said parts, valves, means whereby the movement of the valves effects an increase or decrease of the 55 speed of the motor respectively, electric members respectively controlling said valves, an electric circuit for each of said members, a pneumatically operable circuit making and breaking device included in each of the 60 circuits, valves and connections between said valves and the pneumatically operable circuit making and breaking device whereby said devices are controlled respectively, by 65 said valves, a plurality of electric motors controlling the movement of each of said
- valves, circuit closing means operable periodically under the control of the moving parts, respectively, and a plurality of electric circuits in which the circuit closing means, the electric motors and the circuit making and breaking devices are included, the electrical connections being so arranged, however, that when one of the circuit closing means is actuated in advance of the other a circuit is completed through one of the electric motors with which it is associated to move the valve that is controlled thereby and also closes the circuit in which the other electrical motor is included whereby when the other circuit closing means is moved, said electric motor is energized to continue the actuation of said valve and to thereby continue the pneumatic operation of said circuit making and breaking devices, and connections between the valves whereby when said valves are simultaneously opened they each act to cut off communication between the other valve and the pneumatic circuit making and breaking device controlled by the latter.
18. Mechanism for synchronizing the operations of moving parts, comprising, in combination, a motor for one of said parts, and means for effecting an increase or decrease of the effective strength of the forces exerted upon the motor, said means including pneumatically operable circuit making and breaking devices, valves, and connections between said valves and the pneumatically operable circuit making and breaking devices, said valves controlling the pneumatic forces by which said devices are actuated, a plurality of electric motors for controlling the movement of each of said valves, circuit closing means operable periodically under the control of the moving parts respectively, and a plurality of electric circuits in which the circuit closing means, the electric motors and the circuit making and breaking devices are included, the electrical connections being so arranged, however, that when one of the circuit closing means is actuated in advance of the other a circuit is completed through one of the electric motors with which it is associated to move the valve that is controlled thereby and also closes the circuit in which the other electric motor is included whereby when the other circuit closing means is moved said electric motor is energized to continue the actuation of said valve and to thereby continue the pneumatic operation of said circuit making and breaking devices, and connections between the valves whereby when said valves are simultaneously opened they each act to cut off communication between the other and the pneumatic circuit making and breaking device controlled by the latter.
19. Mechanism for synchronizing the operations of moving parts, comprising, in

combination, a driving motor for one of the parts, a pair of ducts, connections between the ducts and the motor including means controlled by variations of pressure within the ducts for effecting an increase or decrease of the speed of the driving motor, a pair of primary controlling valves, a pair of additional controlling valves, the latter valves when in one position admitting atmosphere to the respective ducts, chambers with which the ducts are respectively brought into communication when the said valves are in their other positions, actuating members to which the additional valves are secured, a pair of additional ducts, each of the latter ducts establishing communication

between one of the primary valves, the actuating member of one of the additional valves, and the controlling chamber of the other additional valve, suction chambers, means for establishing communication between the suction chambers and controlling chambers when the primary valves are opened, actuating members for the primary valves, ducts through which said primary valves are controlled, a plurality of controlling members for each of said ducts and means for actuating said controlling members successively under control of the moving parts respectively.

In testimony whereof I affix my signature.

HEINRICH BOCKISCH.
